JOSEPH B. OKEY, OF INDIANAPOLIS, INDIANA.

Letters Patent No. 73,829, dated January 28, 1868.

IMPROVEMENT IN SPRING DOOR-HOLDERS.

The Schedule referred to in these Letters Patent and making part of the same.

TO WHOM IT MAY CONCERN:

Be it known that I, JOSEPH B. OKEY, of Indianapolis, county of Marion, and State of Indiana, have made new and useful Inventions in Door-Springs; and I hereby declare the following to be a full and exact description of the same, reference being had to the drawings that accompany and form a part of these specifications.

The object of my invention is to provide a spring or device by which a door may be held, when open, at any desired point.

Figure 1, perspective view.

Figure 2, sectional view.

Figure 3, plan view.

Letter A the base; letter B, standard; letter C, spring; letter D, key or pin.

The base, A, may be made in any form to suit the fancy, or that may seem advisable, and if found necessary to prevent its moving too easily on the floor or carpet, may have a roughened under surface. The standard B is cast in connection with the base, A, having an opening through it, whose lower side comes on a level with the top of the base. This standard is made to come just above the coil of the spring C, to steady and keep it in position. Slots e e are made in the base, on each side of the standard, deep enough to admit the thickness of the spring. The spring is made of wire, the extension k thereof in any form or shape desired, the ends coiled around sufficiently to give the elasticity required. At the terminus the two ends are run off in a straight line at the lower part of the coil, as seen at e i in fig. 3, or may be bent down over the edge of the base to keep the coil from turning. The spring thus formed is placed, one part on each side of the standard, and the key D being driven through the opening, holds it firmly in place.

When we desire to have a door open, it is also desirable to have something to hold it at any given point, to prevent its being blown in either direction by the wind, thus slamming the door, or knocking it against articles of furniture or the walls of the house, doing damage to both. Placing my device under the door, having the edge thereof come in the hollow of the spring, will obviate all such inconveniences.

What I claim, and desire to secure by Letters Patent, is—

A device for holding a door in any desired position, when constructed with the base, A, and standard B made in one piece, with the spring C held in position by the key D, substantially as described and set forth.
